Primary Examiner — Vy N Koenig(74) *Attorney, Agent, or Firm* — Klarquist Sparkman, LLP(57) **CLAIM**

The ornamental design for a chair, as shown and described.

DESCRIPTION

FIG. 1 is a perspective view of a chair showing our new design.

FIG. 2 is a front view of the chair of FIG. 1.

FIG. 3 is a rear view of the chair of FIG. 1.

FIG. 4 is a left side view of the chair of FIG. 1.

FIG. 5 is a right side view of the chair of FIG. 1.

FIG. 6 is a top view of the chair of FIG. 1; and,

FIG. 7 is a bottom view of the chair of FIG. 1.

The broken lines in the figures illustrate the environment of the claimed design and form no part of the claimed design.

1 Claim, 4 Drawing Sheets(56)
